OIL BURNER

August Behrsin, Huntington Park, Calif.

Application September 27, 1937, Serial No. 165,816

1 Claim. (Cl. 158—91)

This invention relates to an oil burner construction adapted for use as a burner for oil fed by gravity or pressure and wherein the oil is caused to spread out uniformly into a thin horizontal layer from which it is vaporized in an improved manner.

Among the objects of the invention are to provide an improved combination of means for spreading the oil out in a thin layer and applying to said layer an intensive current of heated air so as to effect the improved vaporization; to provide an improved burner bowl construction wherein the part of the bowl which is subjected to the most intense heat may be detached from the remainder thereof and when necessary replaced by another part performing the same function; to provide an improved multiple mouthed oil feeding means wherein a multiplicity of thin small streams of oil will be fed radially outward from the supply into a thin oil layer which is readily vaporized; to provide a new improved oil spreading element having spiral ribs or grooves which will impart a whirling movement to the oil as it is fed to the vaporizing portion of the device; and to, in general stabilize and render more compact and durable the structure of an oil burner of the class to which the invention pertains.

Other objects, advantages and features of the invention may hereinafter appear.

Referring to the accompanying drawing which illustrates what are at present deemed to be preferred embodiments of the invention,

Fig. 1 is a top plan view of the complete burner, a portion of the deflector being broken away to disclose underlying construction.

Fig. 2 is a vertical mid-section on an enlarged scale taken on line 2—2 of Fig. 1.

Fig. 3 is a bottom plan view of the deflector and the cap thereunder which is formed as a part of said deflector.

Fig. 4 is a vertical mid-section of a modified form of the deflector and cap thereunder to which said deflector is secured.

Fig. 5 is a transverse section looking upwardly from the line 5—5 of Fig. 4.

Referring in detail to the drawing, the burner bowl includes a rim portion 5 which is supported upon the floor portion 6, said floor portion having a peripheral horizontally extending flange 7 in the base of which is an upstanding annular lip 8, thus providing a supporting and centering means for removably mounting said bowl rim 5.

The floor portion 6 of the bowl is provided with an upwardly inclined peripheral portion 9 which,

in combination with the upstanding lip 8 affords a dish-like structure for containing the oil body 11, and the drainage pipe 12 is provided to receive a pipe 13, the mouth of said drainage pipe being slightly below the top of the lip 8 in order that, at no time, the liquid will rise so high within the burner bowl as to overflow the upper edge of said lip.

The floor portion 6 of the burner bowl is furnished with a cup-shaped central downwardly extending part 15 which, by means of a set screw 16, is securable to the upper end of an air supply tube 17. The cup portion 15 above the shank portion 18 thereof which is attached to the pipe 17, is supplied with a tubular upstanding central flange 19 thus affording an annular oil chamber 21 between said flange 19 and the wall of the cup 15 which is spaced outwardly therefrom. With the lower portion of the chamber 21 communicates an oil supply passage 22 into which is screwed the oil supply pipe 23. A drainage plug 24 may be provided for this passage.

A combined oil and air spreading structure 25 is mountable over the open upper end of the flange 19 as shown in Fig. 2. Said structure 25 comprises a body portion 26 of a tubular character furnished near its lower end with an outwardly directed peripheral flange portion 27 the lower surface of which is provided with a series 30 of equally spaced radially projecting ribs or projecting portions 28 shown in bottom plan in Fig. 3, said ribs 28 preferably being outwardly tapered or converging and forming therebetween diverging oil passages whose continuity is only 35 slightly broken by the tips of said ribs. The lower side of the body 26 is also furnished with a downwardly extending annular flange 30, the thickness of said flange being considerably less than the width of the annular oil chamber 21, 40 thus affording an annular oil space 31 outside of said flange which communicates with the spaces 28s between the ribs 28. As shown in Fig. 3 the annular body 26 is provided with a plurality 45 of outwardly directed spacing lugs 29 which maintain the parts in the spaced relation shown in Fig. 2. The annular body 26 above its basal flange 30 is of a proper diameter to fit properly around the annular flange 19. Within the flange 30 there is a space 32 between it and the upstanding tubular flange 19. Said space 32 is provided for convenience in assembling. It avoids the necessity of machining the parts adjacent thereto.

Tracing the course of the oil through the 55

- structure which has been described, the oil enters through the pipe 23, accumulates in the annular oil chamber 21 within the cup 15 and after filling said chamber passes up through the annular oil space 31 after overflowing which it passes horizontally outward through spaces 28s between the ribs 28 and then collects in a shallow annular body 11 upon the bowl floor 6. In order to direct an effective oil vaporizing stream of air down upon the body of oil 11 the tubular oil spreader member 26 is surmounted by a spider 26s preferably made integral therewith, said spider having a body portion 33 which carries an upwardly convexed spreader plate 34, said spreader plate 15 preferably being provided at its center with an upwardly directed apertured lug 35 through which a suitable tool may be inserted for lifting the entire structure 25 from the underlying part of the oil burner construction.
- 20 The detachable rim portion 5 of the burner bowl may be made of a material adapted to withstand higher temperatures than the floor portion of the bowl. This rim portion 5 is subjected to the most intense heat during the operation 25 of the device. It is preferably of a concavo-convex character with its concave face directed downwardly in order to impart a whirling or eddying effect to the air as it is delivered from the deflector 34.
- 30 In Figs. 4 and 5 is shown a modified combined air deflector and oil feeding structure which may be substituted for the structure 25 shown in Fig. 2. This modified structure includes an annular base member 40 having at its lower end a downwardly directed skirt or annular flange 41 which is exteriorly provided with a plurality of spaced vertical centering ribs or lugs 42. At the upper end of the flange 41 a horizontal peripheral outwardly directed flange 43 is provided and each rib 42 of the flange 41 has a horizontally extending portion 44 which overlies said flange 43. The result of this construction is that when the structure shown in Fig. 4 is substituted for the structure 25 of Fig. 2 a series of radial oil outlet passages are provided owing to the fact that the rib portions 44 rest upon the upper surfaces of the floor 6 and at the same time the outer faces of the rib portions 42 abut against the inner side of the cup wall 15.
- 40 At the top of the member 41 of Fig. 4 is provided, integral therewith, a spider or crossbar 46 in the center of which is secured an upstanding screw stem 47. Upon the upper end of this stem 47 screws the body portion 50 of the modified deflector 51. Said modified deflector has a downwardly directed concave face which is provided with a plurality of spirally arranged air whirling ribs 52.

Both of the deflectors shown direct the air 60 downwardly against the annular oil body 11 in

a current shaped as an inverted funnel. The air may be delivered to the concave side of either of the deflectors shown with sufficient force to be deflected downwardly in a current powerful enough to extend out or attenuate in a horizontal direction the annular oil body 11 and cause its outer portion to creep up to or somewhat beyond the periphery of the floor 6 of the bowl. In this extended condition vaporization will take place more rapidly and better combustion will 10 be secured. It will be observed that the shoulder 8 along the juncture of the bowl rim 5 with its body portion, is so positioned as to guard against leakage of the liquid fuel.

As a convenience for lighting the burner an 15 annular seat or groove 27a is provided in the upper face of the spreader flange 27 and in said groove is placed a strip 27b of asbestos or other incombustible, absorbent material, small passages 27c being provided adjacent to said groove to 20 receive small wires 27d to hold said strip 27b in place and to allow oil to ascend from the passages 28s into said groove. When an ignitable liquid fuel is poured or fed into the groove 27a it will be absorbed by the strip 27b and then by 25 applying a flame or other ignition means to said strip, an annular band of fire will result adjacent to the oil body 11 causing thorough ignition of the fuel under the encouragement of the air stream directed downwardly by the deflector. 30

It should be understood that the present disclosure is for the purpose of illustration only and that this invention includes all modifications and equivalents which fall within the scope of the subject matter claimed. 35

What is claimed is:

In an oil burner, a burner bowl having a base portion provided with an upstanding central flange around which is an annular oil chamber, an oil and air spreading member having an annular lower portion which is fitted around the upper end portion of said flange, said spreader having in its lower portion an outwardly directed peripheral flange having downwardly projecting radial ribs which rest upon the floor of said bowl when the spreader is fitted upon said flange, said bowl having an annular space to provide for collecting an annular shallow body of oil around the outer ends of said ribs, means to supply oil to said annular oil chamber and thence to the spaces between said ribs and to said shallow oil body, an air spreading deflector mounted upon the upper portion of said spreader body in a position to direct a current of air of an inverted funnel shape down upon said shallow body of oil, and means to supply a current of air against said deflector to be deflected thereby against said shallow oil body. 45 50 55
